VACUUM CLEANER SUCTION DEVICE Norman E. Ahlsweide, Morton Grove, Ill., assignor to
Birtman Electric Company, a corporation of Illinois

Application May 20, 1952, Serial No. 288,884

6 Claims. (Cl. 230—117)

This invention relates to a vacuum cleaner and particularly to a motor driven suction device for use therein.

In vacuum cleaners and similar machines the suction is ordinarily created by means of a motor driven fan unit. Where a relatively high suction is to be developed in the cleaner, the unit preferably employs a plurality of fan stages. Such a construction is quite simple to build in tank type cleaners as here ample space is usually available for the plurality of stages. However, in the rotary brush type cleaner that is adapted to be propelled over the floor by means of a handle, space is quite limited so that the fan has ordinarily been a single stage vacuum fan. This is true because the propelled rotary brush cleaner can be neither too long where the motor-fan unit is horizontal nor too high where the motor-fan unit is arranged vertically.

The vacuum cleaner of this invention employs a multi-stage fan and motor unit constructed in such a way that the high vacuum of such a fan is obtained without the usual excessive length so that the unit will easily fit into the available space in a motor brush type cleaner.

The invention will be described as related to the embodiment shown in the accompanying drawings. Of the drawings: Figure 1 is a side elevation of a vacuum cleaner embodying the invention with this elevation being partially in section; and Figure 2 is a plan view of the vacuum cleaner of Figure 1.

In the vacuum cleaner shown in the accompanying drawings there is provided a body 10 supported on spaced wheels 11 and 12 and formed at the front end thereof with a suction nozzle 13. Within the body 10 at the front thereof there is provided a chamber 10a adapted to contain a dust intercepting filter unit 14 into which dust laden air is adapted to flow from the nozzle 13. Immediately beneath this chamber 10a is an elongated chamber 10b extending toward the rear of the cleaner and adapted to contain a belt 15 for driving a rotary brush 16.

In order to create a relatively high suction in the vacuum cleaner the rear portion thereof is provided with a suction unit including a motor 17 and a multi-stage fan 18. The motor includes a rotor 19 mounted for rotation with a motor shaft 20 and surrounded by the usual field laminations 21 and field coils 22. Extending through the top of the cleaner body 10 is an ordinary electric cord 23 for supplying electricity to the motor 17. Also attached to the cleaner body at the rear thereof is an ordinary handle for propelling the cleaner and including a pair of bail portions 24 and 25.

The motor shaft 20 is arranged essentially vertically and is supported by top and bottom bearings 26 and 27. The top bearing is supported in an annular flange 28 on the top wall of the cleaner body while the bottom bearing 27 is supported by an annular flange 29 formed as a part of a partition wall 30. This partition wall 30 is provided with an air inlet opening 30a through which air is drawn by the fan 18 from the nozzle 13, through the filter unit 14, up through the fan 18, around the motor 17, and out an exit opening 10c at the rear of the cleaner body.

2

In order to make the suction unit as short as possible and thus avoid excessive height in the cleaner at the rear thereof, a commutator 31 for the motor is positioned between the upper stage 32 and the lower stage 33 of the fan. With this arrangement the upper stage 32 can be located closely adjacent to the rotor 19 and the commutator 31 thus occupies space that is normally wasted in the ordinary multi-stage fan and motor combination. In the embodiment shown the upper stage 32 of the fan 10 is located adjacent to a transverse baffle 34 provided with an air inlet opening 34a for air flowing between the two stages of the fan.

In order to further save space and reduce the overall length of the unit the lower bearing 27 is preferably located within the entrance to the lower fan stage 33. Thus here again the bearing is positioned within a space that is ordinarily wasted in the usual multi-stage fan.

As can be seen in Figure 1, the commutator 31 is of the usual relatively large diameter. Similarly the portion 35 of the motor between the commutator and the rotor 19 is also of large diameter and the portion between the bearing 27 and the commutator 31 is only slightly smaller than the diameter of the commutator. With this arrangement each fan stage can be made of relatively light weight materials. Thus the upper fan stage 32 is constructed of relatively thin parallel sheet metal side portions 36 and 37 having a plurality of fan blades 38 therebetween. The side portion 36 is attached to a relatively heavy plate 39 of considerably less diameter than that of the portion 36 in order to give rigidity to the structure. The lower fan stage 33 is similarly constructed and attached to a similar circular plate 40 at the lower end of the commutator 31. The bottom end of the shaft 20 extends beyond the lower bearing 27 and is shaped to provide a drive spindle 41 for the belt 15, with this spindle also being located with the belt in the bottom chamber 10b.

When the motor driven fan unit is being operated air is drawn in through the inlet opening 34a in the wall 30 and is forced out between the blades in the lower fan stage 33 to the periphery thereof. From this periphery the air is directed by the baffle 34 into the baffle opening 34a and then out between the fan blades 38 at the upper fan stage 32. From here the air flows around the motor 17 and out the exit 10c. With this construction the commutator 31 which is located almost entirely with the chamber 10d defined by the wall 30 and baffle 34 has air directed across it in order that maximum cooling is achieved. Furthermore, space is further conserved by locating the upper end of the commutator 31 within the air inlet opening 34a of the baffle 34.

As is shown in Figure 2 the two brushes 42 for the motor are aligned transversely of the cleaner with each brush being held in a substantially cylindrical housing 43. The brushes are also positioned in the air stream so that maximum cooling is achieved and they are so located as to use space that was formerly wasted.

The baffle 34, the two transverse air straightener baffles attached to the bottom thereof as shown in Figure 1, and the brush holders 43 may be in the form of a single unit 60 insertable into and removable from the rear portion of the cleaner body 10.

Among the advantages of the structure shown and described herein is the conservation of length in the motor and fan unit so that a multi-stage fan can be used in a vertically arranged unit without drastically increasing the height of the cleaner. This is achieved by locating the various parts of the unit in space that was formerly wasted. Another important advantage is that improved cooling of the commutator, brushes, bearings, and other parts of the motor is achieved by locating these parts within or closely adjacent to the suction air stream.

Although the invention has been described as embodied

in a vacuum cleaner, it is believed obvious that the same principles can be used in any motor driven suction device using a combination of a motor and a multi-stage fan where the length of the device is maintained at a minimum.

The foregoing detailed description is given for clearness of understanding only, and no unnecessary limitations should be understood therefrom as modifications will be obvious to those skilled in the art.

I claim:

1. In a vacuum cleaner, an essentially vertical suction unit of relatively short length to reduce the overall height of the cleaner comprising a motor including a shaft and a rotor mounted thereon, a multi-stage fan on the shaft on one side of the motor, a commutator on the shaft between two adjacent fan stages, and a shaft bearing positioned within the inlet of the outermost fan stage. 10

2. In a vacuum cleaner, an essentially vertical suction unit of relatively short length to reduce the overall height of the cleaner comprising a motor including a shaft and a rotor mounted thereon, a multi-stage fan on the shaft on one side of the motor, and a commutator on the shaft between two adjacent fan stages and in contact with the air stream flowing therebetween. 20

3. In a suction device of relatively short length, a motor including a shaft and a rotor mounted thereon, a pair of spaced shaft bearings engaging the shaft on opposite sides of the rotor, a two-stage fan on the shaft between one end of the rotor and a bearing with each stage having a centrally located air inlet, and a commutator on the shaft between the fan stages, one of the bearings being located 25 within the inlet of the outermost fan stage. 30

5 4. In a suction device of relatively short length, a motor including a rotor, a multi-stage fan on one side of the rotor and rotated thereby with each stage having a centrally located air inlet, a commutator on the shaft located between two adjacent fan stages, and a bearing for the rotor engaging the shaft and positioned within the inlet of the outermost fan stage.

5 5. The suction device of claim 4 wherein a pair of commutator brushes are provided between said two fan stages for contact with the air flowing therebetween.

6. In a suction device of relatively short length, a motor including a rotor, a multi-stage fan on one side of the rotor and rotated thereby with each stage having a centrally located air inlet, and a commutator on the shaft located between two adjacent fan stages of said multi-stage fan. 15
